UNITED STATES PATENT OFFICE.

GEORGE B. FEDRICK AND JAMES M. LEE, OF DODGE CITY, KANSAS.

ROTARY PUMP.

1,292,287.

Specification of Letters Patent. Patented Jan. 21, 1919.

Application filed September 5, 1917. Serial No. 189,845.

To all whom it may concern:

Be it known that we, GEORGE B. FEDRICK and JAMES M. LEE, citizens of the United States, residing at Dodge City, in the county 5 of Ford, State of Kansas, have invented a new and useful Rotary Pump, of which the following is a specification.

The subject of this invention is a rotary pump, and the objects of the invention are, 10 first, to provide a rotary pump with novel suction means, second, to provide means for suspending the runner of the pump within the casing, third, to provide pistons which are extended by centrifugal force and cam 15 retracted, fourth, to provide a simple and efficient rotary pump.

With the foregoing and other objects in view which will appear as the description proceeds, the invention resides in the combination and arrangement of parts and in the details of construction hereinafter described and claimed, it being understood that changes in the precise embodiment of the invention hereinafter disclosed, can be 20 made within the scope of what is claimed, 25 without departing from the spirit of the invention.

A practical embodiment of the invention is shown in the accompanying drawing, 30 wherein:

Figure 1 is a plan view of the pump with the casing cover removed;

Fig. 2 is a sectional view taken on the line 2—2 of Fig. 1;

Fig. 3 is a bottom plan view of the cover;

Fig. 4 is a view in elevation of one of the pistons, the head or blade being in section;

Fig. 5 is a central longitudinal section of the check or foot valve casing, the valve 40 shown in place therein, being in elevation.

Referring to the drawings by numerals of reference:

A bowl 1, of circular cross section, forms the main portion of the pump casing, and 45 is provided at the central point of its bottom, with a downwardly projecting cylindrical offset 2, which forms a socket, as seen most clearly in Fig. 2. An outwardly extending annular flange 3 is formed at the 50 upper edge of the bowl, and this flange is provided with spaced apertures 4 for the reception of bolts or the like, by which the top or cover and intake and discharge pipes may be secured in place. At one point in 55 the bottom of the bowl 1, and near the side wall is provided an inlet port 5, adjacent

which an abutment 6 projects inwardly for a short distance from the wall of the bowl 1.

A vertical shaft 7 has its lower end hung in the socket formed by the cylindrical offset 2, and upon this shaft is mounted the rotary element. This rotary element is preferably cast in one piece and consists of a hub 8 to which are secured the horizontally disposed segmental portions 9. Each segmental portion is bounded by upstanding side flanges 10 the outer ends of which are joined by an arcuate flange 11. An aperture 9' may be provided in each segment 9 for the purpose of allowing water which may 70 enter a segment to drain therefrom. The rotary element is secured on the shaft 7 by a set screw 12 or in any other suitable manner.

As will be evident the segments 9 with 75 their side flanges 10 define channels or slots in which the pistons or impeller blades are slidably mounted. These pistons consist of shanks 13 each formed at one end with a head 14 in the upper and lower edge of 80 which is provided a groove for the reception of a packing strip 15. Bores 16 may extend through each head and communicate with the upper and lower slots and within these 85 bores may be mounted rods 17 the ends of which enter apertures in the strips 15 and which rods are surrounded by the coiled compression springs 18 which abut the strips 15 and force them outwardly against the 90 top and bottom of the pump casing.

A longitudinal rib 19 extends along each side of the pistons and is adapted to enter and slide in a groove 20, formed in the face of each flange 10. This structure keeps the pistons in proper vertical position with respect to the rotary member. A pin 21 is 95 threaded in each shank 13, from which it rises, and upon each pin 21 turns a roller 22.

A cover 23 is provided for closing the bowl or casing 1 and this cover is formed 100 with an outwardly extending hub 24 which encircles the shaft 7. Spaced apertures 25 are provided about the cover 23 and are adapted to align with the apertures 4 formed in the flange of the bowl. An outlet port 26 is provided in the cover 23 and is positioned to lie adjacent the abutment 6 on the side opposite to that at which the inlet port 5 opens.

A cam flange 27 depends from the cover 110 23 and is adapted to contact the rollers 22 for the purpose of drawing the pistons inwardly

as they successively pass the abutment 6. The pistons after passing the abutment 6 are again returned to their extended positions by centrifugal force. The cover may be tapped to receive a plug 28 which will permit access for the purpose of oiling the rollers 22.

10 A ball race 29 in which are the balls 30 surrounds the shaft 7 and is seated on the hub 24. An adjusting nut 31 is threaded on the shaft 7 and seats on the ball race 29. By means of this nut the parts are so adjusted that the rotary member is held just clear of the bottom of the bowl 1.

15 The shaft 7 may be coupled to a drive shaft in any suitable manner but is herein shown as connected by a coupling sleeve 32 which is feathered on the end of each shaft as shown in Fig. 2. It is to be noted that the drive shaft 33 does not rest upon the shaft 7 but its weight is supported by other means, thereby relieving the pump structure of this additional strain.

20 An inlet pipe 34 and an outlet pipe 35 are secured to the pump casing for the purpose of conveying water to and from the same.

25 When the pump is situated above water level it is necessary to have a foot or check valve in the inlet pipe. The preferred form of valve used for this purpose is shown in Fig. 5 and consists of a cylindrical valve casing 36 in the lower end of which is a

ring or collar 37 the inner periphery of which is beveled to form a seat for a valve 38. The valve 38 has upstanding curved wings or vanes 39 spaced about it which act to guide the valve and also give it a twisting movement to grind the valve on its seat.

30 The foregoing description is believed to fully set forth the operation of the device without any special description thereof.

Having thus described the invention, what is claimed as new and sought by Letters Patent, is:

35 A rotary pump, comprising a casing provided with an inlet and an outlet port, a rotary member turning in the casing and consisting of a hub, horizontally disposed segmental sections extending from the hub, said sections provided with grooves on their opposed edges, pistons mounted between the sections and normally held in extended positions, ribs on the pistons and adapted to enter the grooves, and a cam on the casing for successively retracting the pistons. 55

In testimony that we claim the foregoing as our own, we have hereto affixed our signatures in the presence of two witnesses.

GEORGE B. FEDRICK.
JAMES M. LEE.
